Atty's.

UNITED STATES PATENT OFFICE.

HAROLD D. BICKFORD, OF WATERVILLE, MAINE.

MOLDER'S FLASK.

Application filed May 20, 1926. Serial No. 110,361.

This invention relates to molders' flasks which are often made of wood or other inflammable material. Such flasks are used in iron or brass foundries to hold the sand for the casting. When the hot molten metal is poured into the mold, gases are formed in the mold at high temperatures. These gases find their way out through the pores and minute voids in the body of the sand and particularly at the parting line, and reach the air through the crack between adjacent members of the flask. Such is the temperature of the gases that they spontaneously burst into flames upon reaching the air. The flames of the burning gases char the outer edges of the members of the flask along the line of meeting before they can be extinguished. This successive charring of this portion of the flask materially shortens the life of the flask and makes repairs or renewals too frequent. An object of my invention is to prevent burning or charring of the edges of the flask members by providing a duct to collect and lead away the hot gases, discharging them into the air at points where no harm will be done if they ignite.

Further advantageous features of construction will be apparent from the disclosure of the invention in the following description of the device and on the drawings, of which:

Figure 1 is a plan view of a molder's flask.

Figure 2 is a side elevation of the same.

Figure 3 is a worm's eye view of a portion of the upper part of the flask as indicated by the line 3—3 of Figure 2.

Figure 4 is a fragmentary section taken on the line 4—4 of Figure 1.

Figure 5 is a section on the line 5—5 of Figure 1.

Figure 6 is a section of the upper part of a flask having a modified form of my invention, the section being taken as on the line 6—6 of Figure 1.

Referring to the drawing in detail, a molder's flask of ordinary construction is illustrated in Figures 1 and 2. As shown, the flask comprises an upper part 10 and a lower part 11 which are normally in superposed relation. While for simplicity the flask shown on the drawing comprises but two parts, it will be understood that as many more parts as may be found desirable or necessary may be used. Where the flask is constructed of wood, each part is preferably

built up of end pieces 12 and side pieces 13, these pieces being secured together by any suitable means such as nails, bolts, or the like. Handles 14 may be provided on the side pieces 13 of the upper part or cope 10 to facilitate manipulation thereof. Dowels 15 may also be provided on the lower face of the cope to enter recesses 16 in the lower part so as to secure mutual registration of the two parts. The dowels 15 are commonly cast on a plate 17 which is set into the contacting face of the upper part 10 of the flask, this base plate 17 resting on a perforated plate 18 set into the contacting face of the lower part of the flask or drag, the perforation in the plate 18 registering with the recess 16 into which the dowel 15 enters. Except for the relatively short plates 17 and 18, the contacting faces between the two parts of a wooden flask as heretofore made are of the wood itself. When molten metal is poured into the sand held by the flask, the extremely high temperatures cause gas to be formed in the sand which works its way out through the voids and interstices thereof and emerges in part between the contacting faces of adjacent parts of the flask. These gases usually emerge at such high temperatures as to ignite spontaneously upon reaching the open air, the flames of the burning gases causing the wood of the flask to catch fire in the vicinity of the crack between the two parts. This injures the flask since the wood thereof is frequently burned or charred considerably before the flames are extinguished. In order to prevent such injury, I provide a channel 19 in one or both of the contacting faces of adjacent parts, this channel preferably extending all the way around the flask so as to provide a duct in which gases may collect as they find their way out between the parts. In order to lead off the gases from the channel 19, I provide one or more vents 20 which may be cut through the wall of one of the parts of the flask or formed in one or more of the plates 17, or both, to connect the channel 19 with the open air at a point spaced from the line of contact of the two parts as shown in Figures 2 and 4. To protect the face of the part in the vicinity of the vent 20 when they are formed in the wall, I may mount a plate 21 of fire-resisting material, such as metal, asbestos, or the like, this plate having a perforation 22 registering with the vent 20. 110

Any desired number of vents 20 may be supplied. In Figure 1, four are shown, one for each corner of the flask, but more or less may be supplied according to conditions.

- 5 5 Where extreme gas conditions are encountered, I may further protect the contacting portions of the parts 10, 11, as shown in Figure 6. In this form, in addition to the channel 19 I provide a metal strip or
- 10 10 piece 23 which may be of any desired shape of cross section and is preferably set into the contacting face of each of the parts 10 and 11, the strip 23 extending from the outer edge of the face inwardly as far as the channel 19. These strips 23 protect the outer edges of the parts 10 and 11 from flames of any gases which may escape between the parts to the open air instead of passing off through the channel 19 and the vents 20.
- 15 15 20 For average gas conditions, the edges may be protected by strips 23 of fire-resistant material without the additional protection afforded by the channel 19. In such cases, the strips may be set into the walls of the 25 parts of the flask as illustrated in Figure 6, or may be in the form of relatively flat strips attached to the outer faces of the parts with one edge flush with a contacting face. Other different forms of sheathing means 30 may be used to protect the edges, such for example as an angle strip set into each part of the flask, the faces of the strip being flush respectively with the outer and contacting faces of the parts.
- 35 35 40 It is to be understood that the invention is not to be limited by the embodiments shown and described herein, but is subject to such changes and modifications as fall within the scope of the appended claims.

I claim:

1. A molder's flask having a plurality of parts normally in superposed relation with contacting faces, one of each pair of adjacent parts being provided with a channel in its contacting face, one of each pair of adjacent parts having a vent connecting said channel with the open air.
- 45 45 50 2. A molder's flask having a plurality of parts normally in superposed relation with contacting faces, one of said parts having a channel in its contacting face extending longitudinally thereof and spaced from the

outer edge thereof, one of said parts being provided with a vent connecting said channel with the open air at a point spaced from 55 the plane of contact of the parts.

3. A molder's flask having a plurality of parts normally in superposed relation with contacting faces, one of said parts having a channel in its contacting face extending 60 longitudinally thereof and spaced from the outer edge thereof, one of said parts being provided with a vent connecting said channel with the open air, and fire-resistant means surrounding said vent for protecting 65 the surface of the flask adjacent to said vent.

4. A molder's flask having a plurality of parts normally in superposed relation with contacting faces, one of said parts having a 70 channel in its contacting face extending longitudinally thereof and spaced from the outer edge thereof, said flask also being provided with vents connecting said channel with the open air, and a plate of fire-resistant 75 material covering the surface of the flask in the vicinity of the vent and having a perforation therethrough registering with said vent.

5. A molder's flask having two parts 80 normally in superposed relation with contacting faces, one of said parts having a channel in its contacting face extending longitudinally thereof and spaced from the outer edge thereof, fire-resistant pieces set 85 into the contacting faces of the flask parts and extending from said outer edge inwardly as far as said channel, said flask also being provided with vents connecting said channel with the open air, and fire-resistant means 90 associated with said vents for protecting the surface of the flask in the vicinity of the vents.

6. A wooden molder's flask having two parts normally in superposed relation with 95 contacting faces, and fire-resistant means set into the outer portions of said contacting faces and flush therewith, whereby the outer portions and edges of the contacting faces are of fire-resistant material.

In testimony whereof I have affixed my signature.

HAROLD D. BICKFORD.
